United States Patent Office

Des. 202,177

Patented Sept. 7, 1965

202,177

PANEL UNIT

William Blau, Evanston, Ill., and Dominic A. Saporito, Birmingham, Mich., assignors, by mesne assignments, to American Screen Products Company, Chicago, Ill., a corporation of Florida

Filed Jan. 9, 1963, Ser. No. 73,103

Term of patent 14 years

(Cl. D13—1)

FIG. 2.FIG. 3.FIG. 4.

FIG. 1 is a perspective view of a single panel of the panel unit shown in FIG. 2,

FIG. 2 is a perspective view of a panel unit showing our new design, the broken lines showing of the door frame being disclosed for illustrative purposes only.

FIG. 3 is a sectional view taken on line 3—3 of FIG. 2.

FIG. 4 is a sectional view taken on line 4—4 of FIG. 3.

FIG. 5 is a view taken along line 5—5 of FIG. 1.

The characteristic features of the design reside in the surface ornamentation. The rear of the unit is plain.

We claim:

The ornamental design for a panel unit, as shown and described.
